UNITED STATES PATENT OFFICE

JOHN W. LIVINGSTON, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY BRAKING APPARATUS

Application filed September 2, 1931. Serial No. 560,717.

My invention relates to railway braking apparatus, and has for an object the provision of means for automatically controlling the braking action of a car retarded in accordance with the speed of a car passing therethrough. Specifically, the present invention is an improvement on apparatus of the type disclosed and claimed in an application for Letters Patent of the United States, filed by Herbert L. Bone on July 9, 1931, Serial No. 549,588, for railway braking apparatus.

I will describe one form of apparatus embodying my invention, and will then point out the novel features thereof in claims.

The accompanying drawing is a diagrammatic view illustrating one form of apparatus embodying my invention.

Referring to the drawing, the reference characters 1 and 1^a designate the track rails of a stretch of railway track over which cars normally move in the direction indicated by the arrow under such conditions that it is desirable to control the speed of the cars. For example, the stretch of track here shown might be in a classification yard of the "hump" type through which cars move under the influence of gravity. It is obvious that in service of this character, the speed of individual cars or strings of cars will vary through wide limits depending, among other things, upon the speed at which they go over the hump, the temperature, the weight of the car and contents, and the condition of the car as to whether it is a free running car or otherwise.

In order to control the speed of cars, the stretch of track shown in the drawing is provided with a car retarder R comprising, in the form illustrated, a pair of braking bars 2 and 3, extending parallel with, and located on opposite sides of rail 1, and a similar pair of braking bars 2^a and 3^a extending parallel with, and located on opposite sides of rail 1^a.

The braking bars 2, 3, 2^a and 3^a are operated by a fluid pressure motor M comprising a cylinder 4 containing a reciprocable piston 5 which is attached to one end of a piston rod 6. The braking bars 2, 3, 2^a and 3^a are operatively connected with the piston rod

6 of motor M through suitable linkage including a bell crank 7 pivotally supported at point 8, and a lever 9 pivotally supported at point 10. When piston 5 of motor M occupies its extreme right-hand position, in which it is illustrated in the drawings, the braking bars 2, 3, 2^a and 3^a occupy their ineffective or non-braking positions in which they are out of engagement with the wheels of a car traversing rails 1 and 1^a. When piston 5 is moved to its left-hand position, however, as when fluid pressure is admitted to the right-hand end of cylinder 4, the braking bars 2, 3, 2^a and 3^a are moved toward the associated rail to their effective or braking positions in which they will engage the wheels of a car traversing the rails 1 and 1^a to retard the speed of the car.

The motor M is controlled by two magnet valves A and B, each comprising a valve stem 11 biased to an upper position by means of a spring 12, and each provided with a winding 13 and an armature 14. When winding 13 of valve A is deenergized, valve stem 11 is moved to its upper position by spring 12, and under these conditions, the left-hand end of cylinder 4 is connected with atmosphere through a pipe 15 and a port 16. When winding 13 of valve A is energized, however, as illustrated in the drawing, valve stem 11 is moved downwardly to disconnect pipe 15 from port 16, and to connect this pipe with a suitable source of fluid pressure, not shown in the drawing, through a pipe 17. When winding 13 of valve A is energized, therefore, the fluid pressure supplied to the left-hand end of cylinder 4 moves piston 5 toward the right, thereby moving the braking bars to their non-breaking positions.

When winding 13 of valve B is deenergized as shown in the drawing, valve stem 11 of this valve is moved to its upper position, and the right-hand end of cylinder 4 is then connected with atmosphere through a pipe 18 and a port 19. When winding 13 of valve B is energized, however, valve stem 11 of this valve moves downwardly, disconnecting pipe 18 from port 19, and connecting pipe 18 with pipe 17. It will be apparent, therefore, that when valve B is energized, piston

5 is urged toward the left to move the braking bars to their effective positions by a force which is proportional to the pressure of the fluid supplied to the right-hand end of cylinder 4 under these conditions.

The reference character P^{30} designates a circuit controller comprising a Bourdon tube 20, connected with pipe 18, and subjected to the pressure in the right-hand end of cylinder 4. The Bourdon tube 20 controls a contact 21 which is closed at all times except when the pressure exceeds a predetermined amount, such for example, as thirty pounds per square inch, which pressure is preferably enough to cause the braking bars to exert sufficient braking force to slow down a light weight or medium weight car to the lowest speed at which it is desired to have such car leave the retarder, provided the speed at which the car enters the retarder is within the normal operating limits. Circuit controller P^{80} is similar to circuit controller P^{30} , except that contact 21 of this circuit controller is arranged to open at a higher pressure than contact 21 of circuit controller P^{30} . For example, the parts may be so proportioned that contact 21 of circuit controller P^{80} will be closed for all pressures below eighty pounds per square inch, but will be open for all pressures above eighty pounds per square inch, this latter pressure being sufficient to cause the braking bars to retard a heavy car the desired amount as the car passes through the retarder provided the speed at which the car is moving when it enters the retarder is within the normal operating limits.

The valve B is controlled by the circuit controllers P^{30} and P^{80} , by a manually operable lever L, and by a control relay C. The manually operable lever L, in the form here shown, is capable of assuming three positions, indicated by dotted lines in the drawing, and designated by the reference characters p^0 , p^1 and p^2 , respectively. Operatively connected with lever L are two contact arms 22 and 23. The contact arm 22 cooperates with a contact segment 24 to close a contact 22-24 when lever L occupies either its p^1 or p^2 position, or any position intermediate these two positions. The contact arm 23 cooperates with three fixed contacts 25, 26 and 27 to close a contact 23-25, 23-26, or 23-27, according as lever L occupies its p^0 , p^1 , or p^2 position, respectively.

The lever L and relay C in addition to controlling the valve B also control the valve A.

As shown in the drawing, lever L occupies its p^0 position, and relay C is deenergized. Under these conditions, all circuits for valve B are open and a circuit is completed for valve A which passes from a suitable source of current, here shown as a battery D, through contact 23-25 of lever L, wire 39, winding 13 of valve A, and wires 38 and 33

back to battery D. Valve B is therefore deenergized and valve A is energized, so that the right-hand end of cylinder 4 is vented to atmosphere and the left-hand end of cylinder 4 is supplied with fluid pressure. Piston 5 is therefore moved to its extreme right-hand position in which position the braking bars are held in their ineffective or non-braking position.

If, now, with relay C remaining deenergized, lever L is moved to its p^1 position, the circuit just traced for relay A will become interrupted at contact 23-25 of lever L, and a circuit for valve B will become closed at contact 23-26 of lever L, this latter circuit passing from battery D through contact 23-26 of lever L, wire 28, back contact 29-29^b of relay C, wire 30, contact 21 of circuit controller P^{30} , wires 31 and 37, winding 13 of valve B, and wires 32 and 33 back to battery D. As a result, valve A will become deenergized and will vent the left-hand end of cylinder 4 to atmosphere, and valve B will become energized and will admit fluid to the right-hand end of the cylinder until the pressure in this end of the cylinder exceeds thirty pounds per square inch, at which time contact 21 of circuit controller P^{30} will open and will deenergize valve B until the pressure again decreases below thirty pounds per square inch. It will be apparent, therefore, that when lever L occupies its p^1 position, and relay C is deenergized, the braking bars will be held in their braking positions by a pressure of approximately thirty pounds per square inch, which pressure, as previously pointed out, is normally sufficient to cause the braking bars to slow down a light weight or medium weight car to the slowest speed at which it is desired to have the car leave the retarder.

If, when lever L occupies its p^1 position, relay C becomes energized, the circuit just traced for valve B will become interrupted at back contact 29-29^b of relay C, and another circuit for valve A will become closed which passes from battery D through contact 23-26 of lever L, wire 28, front contact 29-29^a of relay C, wires 40 and 39, winding 13 of valve A, and wires 38 and 33 back to battery D. Valve B will therefore become deenergized, and valve A will become energized. As a result, the braking bars will be moved to their ineffective or non-braking positions in a manner which will be readily understood from the foregoing, and from an inspection of the drawing.

If lever L is moved to its p^2 position when relay C is deenergized, all circuits for valve A will be open, and a circuit for valve B will become closed which passes from battery D through contact 23-27 of lever L, wire 34, back contact 35-35^b of relay C, wire 36, contact 21 of circuit controller P^{80} , wire 37, winding 13 of valve B, and wires 32 and 33 back

to battery D. Under these conditions, valve A will be deenergized and valve B will become energized and will admit fluid to the right-hand end of cylinder 4 until the pressure in this end of the cylinder exceeds eighty pounds per square inch, at which time contact 21 of circuit controller P⁸⁰ will open, and will deenergize valve B until the pressure again decreases below eighty pounds per square inch. It will be apparent, therefore, that under these conditions, the braking bars will be held in their braking positions by a pressure of eighty pounds per square inch, which pressure, as previously pointed out, is normally sufficient to cause the braking bars to slow down a heavy car to the slowest speed at which it is desired to have the car leave the retarder.

If relay C becomes energized when lever L occupies its p^2 position, the circuit last traced for valve B will be interrupted at back contact 35—35^b of relay C so that valve B will become deenergized, and a third circuit for valve A will become closed at front contact 35—35^a of relay C. This third circuit for valve A passes from battery D through contact 23—27 of lever L, wire 34, front contact 35—35^a of relay C, wires 41, 40 and 39, winding 13 of valve A, and wires 38 and 33 back to battery D. Due to this third circuit, valve A will become energized, and since valve B is now deenergized, the braking bars will be moved to their non-braking positions.

It will be apparent from the foregoing that when lever L occupies its p^1 or p^2 position, the braking bars will occupy their braking or non-braking positions according as relay C is deenergized or is energized. According to my present invention, I provide means for controlling relay C in such manner that this relay will normally be deenergized, but that this relay will become energized if the speed of a car which is being retarded by the retarder decreases below a selected one of a plurality of speeds. As here shown, these means for controlling relay C comprise a plurality of treadles 42^a, 42^b, 43^a and 43^b. In the particular embodiment illustrated, the treadles 42^a and 42^b are located between the rail 1^a and the braking bar 2^a adjacent the entrance and leaving ends, respectively, of the retarder, and are so arranged that each of these treadles will be depressed by each wheel of a car running on rail 1^a. The treadles 43^a and 43^b are located opposite the treadles 42^a and 42^b, respectively, between the braking bar 3 and the rail 1, and are so arranged that each of these treadles will become depressed by each car wheel running on rail 1. Each of the treadles 42^a, 42^b, 43^a and 43^b may be of the usual spring biased type, and will return to its normal position as soon as the car wheel has departed from the treadle. The lengths of the treadles 42^a and 42^b may be varied as conditions require, but the lengths

of these treadles will usually be equal and will preferably be less than half the distance between adjacent car wheels on the same car truck. The lengths of the treadles 43^a and 43^b will also usually be equal, but each of these latter treadles will preferably be shorter than the opposite treadle 42, and will be so arranged that it will become depressed shortly before the opposite treadle 42 returns to its normal position, but will return to its normal position at the same instant or immediately before the opposite treadle 42 returns to its normal position. The treadle 42^a controls a contact 44 which, as here shown, is normally open, but which is arranged to become closed when treadle 42^a becomes depressed, and to subsequently remain closed until this treadle returns to its normal position. The treadle 42^b similarly controls a contact 45 which is normally open, but which becomes closed when the treadle 42^b becomes depressed and subsequently remains closed until this treadle returns to its normal position. It will be apparent, therefore, that the time interval during which the contacts 44 and 45 are closed when a car wheel is passing the associated treadle 42^a or 42^b will depend upon the speed of the car. The treadle 43^a controls a contact 46 in such manner that this contact will be closed when the treadle occupies its normal position but will become open when this treadle becomes depressed, and the treadle 43^b controls a contact 47 in a similar manner.

The means for controlling relay C also comprises a plurality of timing relays T^a and T^b which, as here shown, have slow pick-up characteristics. The timing relays T^a and T^b are connected with a pair of line wires 59 and 60 over the contacts 44 and 45, respectively, and the line wires 59 and 60, in turn, are connected with a suitable source of energy, here shown as a battery E, through a rheostat F. It will be apparent, therefore, that if the arm 48 of rheostat F engages any of the taps of the rheostat except the "off" tap 61, when a car wheel depresses one of the treadles 42^a or 42^b, the timing relay T controlled by such treadle will become energized and will remain energized for a time interval which depends upon the speed of the car. If this time interval is longer than the pick-up time for such relay T, this relay will close its armature, thus closing its front contact 49, but if this time interval is shorter than the pick-up time for such relay T, the armature of the relay, and hence, the contact 49 controlled thereby, will remain open. The relays T^a and T^b are so constructed that their pick-up time may be increased or decreased by decreasing or increasing their energization, and it follows that by moving the arm 48 of rheostat F toward the left, the car speed at which these relays will pick up may be increased, there being as many different car

speeds as there are different taps on the rheostat. The parts are preferably so proportioned, that when the arm 48 of rheostat F is engaging the tap in which all the resistance of the rheostat F is cut in, the relays T^a and T^b will pick up their armatures when a car which is being retarded by the retarder is moving at the slowest speed at which it is desired to have cars leave the retarder.

10 The rheostat F, which functions as a speed controller, and the lever L which controls the braking force exerted by the braking bars, will usually be located adjacent each other in a control cabin in such positions that they can be conveniently operated by the same operator.

15 Relay C is provided with two pick-up circuits each of which includes a suitable source of current here shown as a battery G, and a front contact 49 of a different one of the relays T. It will be apparent, therefore, that if either of the relays T^a or T^b becomes energized for a sufficient interval of time to close its front contact 49, relay C will also 20 become energized.

25 Relay C is further provided with a stick circuit which passes from battery G through wires 50 and 51, contact 22-24 of lever L, wire 52, front contact 53 of relay C, wire 54, contact 46, wire 55, contact 47, wires 56, 57 and 58, and the winding of relay C back to battery G. It will be noted that this stick circuit is closed when and only when lever L occupies its p¹ or p² position, the treadles 30 43^a and 43^b both occupy their normal position, and relay C is energized.

35 As shown in the drawing, arm 48 of rheostat F occupies the position in which all of the resistance of the rheostat is cut in. 40 Relays T^a and T^b are both deenergized, and both pick-up circuits for relay C are therefore open. The stick circuit for relay C is also open, and relay C is therefore deenergized. Lever L occupies its p⁰ position. The 45 braking bars therefore occupy their non-braking positions in which they are out of engagement with the wheels of a car traversing the stretch of track shown in the drawing.

50 In explaining the operation of the apparatus as a whole, I will assume that a car which is travelling at a relatively high speed is approaching the retarder, and that it is desired to have the car leave the retarder at a predetermined reduced speed. The operator will therefore first move the braking bars to their braking position by moving lever L to its p¹ or p² position, depending upon the 55 weight of the car, and he will then move arm 48 of rheostat F to the position which will cause the relays T to close their front contacts 49 at the particular speed at which it is desired to have the car leave the retarder, which speed I will term "control" speed. As 60 the car moves through the retarder, each

time a wheel of the car depresses the treadle 42^a or 42^b, the associated relay T^a or T^b will become energized, but as long as the speed of the car is above control speed, neither of these relays will close its front contact 49. 70 Relay C will therefore remain deenergized, and the car retarder will therefore continue to slow down the car. As soon, however, as the retarder has slowed down the car to a speed which is equal to, or less than, control speed, and a wheel of the car passes one of the treadles 42, the associated relay T will close its front contact 49, and relay C will then become energized. When relay C becomes energized, the braking bars will be 75 moved to their non-braking positions in the manner previously described, and it will be apparent, therefore, that no further retardation of the car will take place as long as relay C remains energized. Relay C will remain energized until lever L is restored to its p⁰ position, unless the car again attains a speed which is greater than control speed before the car has departed entirely from the retarder. For, as long as the speed of the 80 car is below control speed and contact 22-24 of lever L is closed, if no wheel of the car is depressing one of the treadles 43^a or 43^b, the stick circuit previously described for relay C will be closed, and if a wheel of the 85 car is depressing one of the treadles 43, so that the stick circuit previously described for relay C is open, then one of the pick-up circuits for relay C will be closed at the front contact 49 of the relay T which is controlled by the treadle 42 which is opposite the depressed treadle 43. Assuming, however, that the car again attains a speed which is greater than control speed before the car has departed entirely from the retarder, then as soon as a car wheel depresses one of the treadles 90 43, the stick circuit for relay C will become interrupted, and the front contact 49 of both relays T will then be open so that both pick-up circuits for relay C will be open, and as 95 a result, relay C will become deenergized. When relay C becomes deenergized, the braking bars will, of course, again be moved to their braking positions to again retard the car. It will be seen, therefore, from the foregoing, that with apparatus embodying my invention, the braking action of the retarder will automatically be controlled in accordance with the speed of the car, and the car 100 will leave the retarder at a speed which depends upon the setting of rheostat F. 115

120 It should be noted that if the car leaves the retarder at a speed which is less than control speed, relay C will remain energized by virtue of its stick circuit until lever L is subsequently restored to its p⁰ position or until the wheel of another car, moving at a speed greater than control speed depresses contact 43^a. When lever L is restored to its p⁰ position, the stick circuit for relay C will become inter- 130

rupted at contact 22—24 of lever L, and relay C will then become deenergized. All parts will then be restored to their normal positions, in which they are illustrated in the drawing.

5 If the operator desires to retain complete manual control of the retarder, he may do so by moving arm 48 of rheostat F into engagement with the "off" tap 61. When arm 10 48 occupies this latter position, the relays T^a and T^b will not become energized when the treadles 42^a and 42^b are depressed, and relay C will therefore remain deenergized regardless of the speed of the car. It will be apparent, therefore, that under these conditions, 15 the braking bars will always occupy the positions corresponding to the setting of lever L.

One advantage of railway braking apparatus embodying my invention is that it provides an extremely simple and effective means 20 for controlling the braking action of a car retarder in accordance with the speed of cars which are being retarded by the retarder.

Although I have herein shown and described only one form of railway braking apparatus embodying my invention, it is understood that various changes and modifications may be made therein within the scope of the appended claims without departing from the 30 spirit and scope of my invention.

Having thus described my invention, what I claim is:

1. Railway braking apparatus comprising a braking bar located in the trackway adjacent a track rail, a first relay, means controlled by said first relay for controlling said braking bar, a plurality of other relays, means controlled by each of said other relays for controlling said first relay; a plurality of 25 devices disposed in pairs along the trackway, the devices of each pair being so arranged that the first device will become operated each time a car wheel passes a first fixed point and will be restored to its normal condition when the car wheel passes a second fixed point located a measured distance in advance of said first fixed point and that the second device will become operated each time a car wheel passes a third point intermediate said first and second points and will be restored to its normal condition when the car wheel passes said second point, means controlled by said first device of each pair for controlling a different one of said other relays, and means controlled by all of said second devices for controlling said first relay.

2. Railway braking apparatus comprising a braking bar located in the trackway; a plurality of devices disposed in pairs along the trackway, the devices of each pair being so arranged that the first device will become operated each time a car wheel passes a first fixed point and will be restored to its normal condition when the car wheel passes a second fixed point located a measured distance in

advance of said first fixed point and that the second device will become operated each time a car wheel passes a third point intermediate said first and second points and will be restored to its normal condition when the car wheel passes said second point, a plurality of relays one controlled by said first device of each pair and each arranged to become energized when the associated device is operated, a control relay, means for energizing said control relay when any of the other relays is energized, other means for energizing said control relay effective when and only when said control relay has once been energized and said second device of each pair occupies its normal condition, and means controlled by said control relay for controlling said braking bar.

3. Railway braking apparatus comprising a braking bar located in the trackway, a plurality of devices disposed in pairs along the trackway, the devices of each pair being so arranged that the first device will become operated each time a car wheel passes a first fixed point and will be restored to its normal condition when the car wheel passes a second fixed point located a measured distance in advance of said first fixed point and that the second device will become operated each time a car wheel passes a third point intermediate said first and second points and will be restored to its normal condition when the car wheel passes said second point, a plurality of timing relays one controlled by said first device of each pair and each arranged to become energized when the associated device is operated, a control relay, means for energizing said control relay when any one of said timing relays is energized, other means for energizing said control relay effective when and only when said control relay has once been energized and said second device of each pair occupies its normal condition, and means controlled by said control relay for controlling said braking bar.

4. Railway braking apparatus comprising a braking bar located in the trackway adjacent a track rail, a pressure responsive device for moving said braking bar into position to engage a part of a car to retard the speed of the car, a first relay, means controlled in part by said first relay for supplying pressure to said pressure responsive device, a plurality of timing relays, means controlled by each of said timing relays for controlling said first relay, a plurality of devices disposed in pairs along the trackway, the devices of each pair being so arranged that the first device will become operated each time a car wheel passes a first fixed point and will be restored to its normal condition when the car wheel passes a second fixed point located a measured distance in advance of said first point and that the second device will be operated each time a

car wheel passes a third point located intermediate said first and second points and will be restored to its normal condition when the car wheel passes said second point, a plurality of contacts one controlled by each of said devices, means controlled by each of the contacts which are controlled by said first devices for controlling a different one of said other relays, and means controlled by all of the contacts which are controlled by said second devices for controlling said first relay.

5. Railway braking apparatus comprising a braking bar located in the trackway adjacent a track rail, a pressure responsive device for moving said braking bar into position to engage a part of a car to retard the speed of the car, a first relay, means controlled in part by said first relay for supplying pressure to said pressure responsive device; a plurality of devices disposed in pairs along the trackway, the devices of each pair being so arranged that the first device will become operated each time a car wheel passes a first fixed point and will be restored to its normal 20 condition when the car wheel passes a second fixed point located a measured distance in advance of said first point and that the second device will become operated each time a car wheel passes a third point located intermediate said first and second points and will be restored to its normal condition when the car wheel passes said second point, a plurality of contacts one controlled by each of said devices and each arranged to be operated 25 during the entire time that the associated device is operated, a plurality of timing relays one controlled by each of the contacts which are controlled by said first devices, and means controlled by each of said timing relays and 30 by all of the contacts which are controlled by said second devices for controlling said first relay.

6. Railway braking apparatus comprising a braking bar located in the trackway adjacent a track rail, a pressure responsive device for moving said braking bar into position to engage a part of a car to retard the speed of the car, a first relay, means controlled in part by said first relay for supplying 35 pressure to said pressure responsive device, a plurality of devices disposed in pairs along the trackway, the devices of each pair being so arranged that the first device will become operated each time a car wheel passes a first fixed point and will be restored to its normal condition when the car wheel passes a second fixed point located a measured distance in advance of said first point while the second device will be operated each time a car 40 wheel passes a third point located intermediate said first and second points and will be restored to its normal condition when the car wheel passes said second point, a plurality of contacts, one controlled by each of said devices and each arranged to be operated 45 during the entire time that the associated device is operated, a plurality of timing relays one controlled by each of the contacts which are controlled by said first devices, and means controlled by each of said timing relays and 50 by all of the contacts which are controlled by said second devices for controlling said first relay.

60

ing the entire time that the associated device is operated, a plurality of other relays, means controlled by each of the contacts which are controlled by said first devices for controlling a different one of said other relays, a plurality of pick-up circuits for said first relay each controlled by a contact of a different one of said other relays, and a stick circuit for said first relay including its own front contact and all of the contacts which are controlled by said second devices.

7. Railway braking apparatus comprising a braking bar located in the trackway, a control relay, means for moving said braking bar to a braking or a non-braking position according as said control relay is deenergized or energized; a plurality of devices disposed in pairs along the trackway, the devices of each pair being so arranged that the first device will become operated each time a car wheel passes a first fixed point and will be restored to its normal condition when the car wheel passes a second fixed point located a measured distance in advance of said first fixed point and that the second device will become operated each time a car wheel passes a third point intermediate said first and second points and will be restored to its normal condition when the car wheel passes said second point; a plurality of normally open contacts, one controlled by said first device of each pair and each arranged to become closed when the associated device is operated and to remain closed until the associated device is restored to its normal condition, a plurality of timing relays; a circuit for each of said timing relays including a source of current, a rheostat and a different one of said normally open contacts; a plurality of pick-up circuits for said control relay each controlled by a front contact of a different one of said timing relays, a plurality of normally closed contacts one controlled by said second device of each pair and each arranged to become opened when the associated device is operated and to remain open until the associated device is restored to its normal condition, and a stick circuit for said control relay including its own front contact and all of said normally closed contacts.

In testimony whereof I affix my signature.
JOHN W. LIVINGSTON.
